CLAIM

I claim the ornamental design for the universal napkin dispenser cartridge, as shown and described.

DESCRIPTION

FIG. 1 is an angled perspective view of the universal napkin dispenser cartridge.

FIG. 2 is an angled perspective view of an alternate embodiment of the universal napkin dispenser cartridge of FIG. 1. FIG. 3 is a front view of the universal napkin dispenser cartridge shown in FIG. 1.

FIG. 4 is a front view of the universal napkin dispenser cartridge shown in FIG. 2.

FIG. 5 is a back view of the universal napkin dispenser cartridge shown in FIG. 1.

FIG. 6 is a back view of the universal napkin dispenser cartridge shown in FIG. 2.

FIG. 7 is the left side view of the universal napkin dispenser cartridge shown in FIGS. 1 and 2 the right side being a mirror image.

FIG. 8 is a top view of the universal napkin dispenser cartridge shown in FIG. 1.

FIG. 9 is a top view of the universal napkin dispenser cartridge shown in FIG. 2; and,

FIG. 10 is a bottom view of the universal napkin dispenser cartridges shown in FIGS. 1 and 2.
